UNITED STATES PATENT OFFICE

GEORGE A. BERING, OF BERKELEY, CALIFORNIA

BUTTON

Application filed May 3, 1930. Serial No. 449,546.

This invention relates to improvements in buttons and has particular reference to a button fastening device that eliminates the necessity of sewing the buttons to goods.

The principal object of this invention is to provide a simply constructed and economical button device that can be readily and quickly attached by an inexperienced person to various types of garments.

A further object is to provide a device that is exceedingly durable and efficient in use and when applied to a garment is neat and attractive in appearance.

Other objects and advantages will be apparent during the course of the following description.

In the accompanying drawings forming a part of this specification and in which like numerals are employed to designate like parts throughout the same,

Figure 1 is a front elevation of the button as applied to a garment such as the front of a coat,

Figure 2 is a rear elevation of the button on the opposite side of the coat,

Figure 3 discloses the perspective views of the various parts that constitute the button,

Figure 4 is a transverse vertical section through the button and garment, the view being taken on the line 4—4 of Figure 1, and

Figure 5 is a front elevation of the button base and with a rear covering plate attached thereto.

In the accompanying drawings wherein for the purpose of illustration is shown a preferred embodiment of my invention, the numeral 6 designates a portion of a garment to which a button is attached. The button per se involves in its construction a front button member 7, a wire flexible member 8, a base member 9 and a rear button plate 10. It will be noted that the button member 7 has provided therein a plurality of openings 11 adapted to receive therein the wire 8 which wire penetrates the goods 6 and thereafter enters the apertures 12 formed in the base 9. As disclosed to advantage in Figures 3, 4 and 5, it will be noted that the member 10 is equipped with spaced flanges 13

which are folded over the marginal edges of the base member 9 which member 10 serves not only to retain the wire 8 in place but also enhances the attractiveness of the button on the rear side of the garment.

In Figure 4 I have disclosed to advantage the manner in which the wire after entering the apertures 12 of the base member 9, is twisted so as to positively retain the button on a garment such as a coat. While I have shown four apertures 12 in the base 9 it is readily understood that two openings can be employed to fulfill the desired purpose of allowing the wire 8 to pass through the openings. A number of openings are shown in the base 9 to permit a more convenient insertion of the wire 8. In Figure 4 the manner in which the parts of the button are held together is illustrated and it will be obvious that as the wire 8 is inserted in the front button member 7, the ends of the wire pierce the goods 6, and after piercing the goods the ends pass through the base member 9. The ends are then twisted so that displacement of the wire from the button members will be eliminated. The flanges 13 of the rear button plate 10 are inwardly bent so as to engage the outer periphery of the base member 9. With this type of device I have found from experience that the inexperienced person can secure a button to a garment and when so secured the button will be retained indefinitely on the coat without danger of accidental loss of the same. This type of button entirely eliminates the necessity of sewing and when applied to a garment is exceedingly attractive in appearance and efficient in use.

It is to be understood that the form of invention herewith shown and described is to be taken as a preferred example of the same and that various changes relative to the material, size, shape and arrangement of parts may be resorted to without departing from the spirit of the invention or the scope of the subjoined claim.

Having thus described my invention, I claim:

A button construction comprising a front button member having a plurality of open-

ings therein, a base member likewise equipped with a plurality of openings therein, and a flexible metal element adapted to penetrate a garment and serving to connect said front button member and said base member, and a rear button plate positioned over said base member, said rear button plate having a plurality of spaced flanges provided thereon for engaging the front face of said base member.

10 In testimony whereof I affix my signature.
GEORGE A. BERING.
